(57) **CLAIM**

(21) Appl. No.: **29/146,105**

The ornamental design for the “yarn feeder with fixed drum
for knitting machines”, as shown and described.

(22) Filed: **Aug. 6, 2001**

DESCRIPTION

(30) **Foreign Application Priority Data**

Feb. 27, 2001 (IT) TO01O0060
FIG. 1 is a perspective view of the yarn feeder with fixed
drum for knitting machines, showing our new design;
(51) LOC (7) Cl. **15-06**
(52) U.S. Cl. **D15/78**
FIG. 2 is a front view thereof;
(58) Field of Search D32/66, 78; 139/452;
66/132 R, 132 T; 242/47.01-47.03, 47.12,
365.6
FIG. 3 is a rear view thereof;
FIG. 4 is a right side view thereof;
FIG. 5 is a left side view thereof;
FIG. 6 is a top view thereof; and,
FIG. 7 is a bottom view thereof.
